CONTROL MEANS FOR INTERNAL-
COMBUSTION ENGINESRalph Miller, Milwaukee, Wis., assignor to Nord-
berg Manufacturing Company, Milwaukee, Wis.,
a corporation of Wisconsin

Application July 31, 1948, Serial No. 41,794

9 Claims. (Cl. 123—32)

1

My invention relates to an improvement in control means for internal combustion engines and has for one object to provide heat responsive means for controlling the inflow of scavenging air.

Another object of my invention is to provide means responsive to exhaust temperatures for controlling the rate of air flow to the combustion chamber.

Another object is to provide an improved air control valve and actuating means therefor.

Another object is to provide an improved means for locking the air control valve in advanced position.

Another object is to provide an improved heat responsive assembly for actuating the air flow control valve.

Other objects will appear from time to time throughout the specification and claims.

In internal combustion engines, and particularly in engines of the gas diesel type, it is advantageous to reduce the quantity of air which is taken into the cylinder when the load is reduced, so that the air-fuel ratio at all loads will remain substantially constant. When the air is thus regulated with the load, it is found that the exhaust gas temperature remains substantially constant at all loads. I provide means and a method of controlling and regulating the air flow to the combustion space during the suction stroke in such a manner as to maintain a substantially constant exhaust temperature. It is known that as the air-fuel ratio is reduced, the exhaust gas temperature increases. Conversely, the exhaust gas temperature decreases as the air-fuel ratio increases.

My invention is illustrated more or less diagrammatically in the accompanying drawing which shows a sectional view through an engine embodying my invention.

Like parts are indicated by like characters throughout the specification and drawings.

Referring to the drawing, 1 is a cylinder, 2 a piston mounted for reciprocation therein, 3 a cylinder head. 4 is an exhaust valve, 5 an intake valve, 6 a spray nozzle for liquid fuel, 7 a gas fuel supply valve. 8 is the exhaust passage leading from the exhaust valve 4 to the exhaust pipe 9. 10 is a bulb housing in the exhaust pipe 9 whose purpose will hereinafter appear. 11 is the intake passage communicating with the intake valve 5 adapted to receive scavenging air through the air scavenging control valve 12, the air being supplied by a pressure passage 13 from any suitable source of scavenging air.

In the bulb housing 10 is a bulb 14 adapted to

2

contain mercury or other suitable heat expansible liquid or fluid. 15 is a conduit leading from the bulb 14 to the expansible motor bellows 16. 17 is a piston rod actuated by the bellows 16 in response to pressure generated in the bulb 14 adapted to actuate the balance piston 18 in the motor cylinder 19.

20 20 is a pipe communicating with the interior of the cylinder between the heads 21 and 22 of the balanced piston valve. It receives hydraulic fluid under pressure from any suitable source not here illustrated. 23, 24 are exhaust pipes leading from the opposed ends of the cylinder 19. 25, 26 are hydraulic fluid pipes each communicating at one end with the cylinder 19 and communicating at the other end with a motor cylinder 27 containing a piston 28. The pipe 25 communicates with the cylinder on the underside of the piston 28, the pipe 26 communicates with the pipe on the upper side of the piston 28.

27 29 is a piston rod connected by means of linkage 30 to the valve stem 31 of the control valve 12. As indicated in this particular exemplification the control valve stem 31 carries two inclined valve discs 32 movable toward and from apertures 33 in valve walls 34 so that with the parts in the position shown, the valves 32 are partly unseated and movement of the valve stem 31 will open and close said valves between their 30 working limits. 35 is a fixed aperture not under control of the valves.

36 36 With the parts in the position shown in the drawing, the piston 28 is hydraulically locked against movement because the two ends of the pipes 25 and 26 are closed by the piston heads 21 and 22. If the temperature in the exhaust pipe changes it will cause movement of the balanced valve 19 in one direction or the other. If the temperature increases, the contents of the bulb 14 will expand, the valve 18 will move to the right. If temperature decreases, the valve will move to the left.

37 37 If the valve 18 moves to the right in response to an increase in temperature, hydraulic fluid entering into the pipe 20 will as the head 22 uncovers the end of the pipe 26 pass down through the pipe 26, tending to move the piston 28 upwardly. At the same time, however, the piston head 21 will have opened the pipe 25 to permit hydraulic fluid to be forced from above the piston 28 out through the pipe 25 and discharged through the pipe 23. This tends to open the valve 12 to increase the amount of scavenging air admitted to the engine and this situation will 50 55 continue until the temperature in the exhaust

3

pipe falls sufficiently to cause the bulb 14 to cool enough to move the piston 18 back to the central locking position at which time the valve 33 will be locked in proper position.

If on the other hand the temperature in the exhaust pipe falls, the opposite cycle of events takes place. Pressure is introduced through the pipe 25 to lower the piston 28 while hydraulic fluid escapes through the pipes 26 and 24.

Thus slight temperature variations in the exhaust are immediately compensated for by adjustment of the valve 12 and as soon as the adjustment has taken place and the valve 12 has sought a new position conforming to the changed engine conditions which result in proper exhaust temperature the valve is automatically locked in proper position. Of course, the opening 35 always permits the introduction of a minimum of scavenging air no matter what the valve position.

The link 39 is a two-part link, the two parts being joined by a nut 40 in which the two ends of the link are oppositely threaded. The nut 40 carries on its outside periphery thereof a gear 41 in mesh with a rack 42 adapted to be reciprocated by the governor of the engine or by any other suitable means not herein shown forming no part of the invention, for the purpose of changing the relative positions of the work piston 28 and the valve 33.

It will be realized that whereas I have described and shown an operative device, still many changes might be made in the size, shape, number and arrangement of parts without departing materially from the spirit of my invention. I wish, therefore, that my showing be taken as in a broad sense diagrammatic and illustrative rather than limiting me to the precise showing.

The use and operation of my invention are as follows:

The parts as illustrated are in for example such position that the air fuel ratio will cause the engine to operate at exhaust temperature of 750 degrees F. though of course other temperatures might be desirable. The piston 28 can move freely in the work cylinder 27 from end to end thereof depending on where the pressure is applied. The piston valve 18 is free to reciprocate in the cylinder 19 under the influence of the bellows 16 which translates change in temperature as applied to the bulb 14 into movement of the control piston 18.

The control mechanism is shown in position for a steady condition, which may for example be one-half load, and an exhaust temperature, let us say of 750 degrees F. The valve 33 is held in the position shown in the drawing by the piston 28. The piston 28 is locked with hydraulic fluid at each side and with the connections between the work cylinder 27 and the control cylinder 19 closed by the lands of the piston. If now the load on the engine increases, the engine governor, which is not herein shown, will admit more fuel to the combustion chamber of the individual cylinders. The immediate result is to increase the exhaust gas temperature, because the valve 33 is set to position the quantity of air suitable for half load. In response to the increase in exhaust temperature, the bulb 14 causes a movement to the right of the bellows 16 referring to the position of the parts in the drawing. This moves the piston 18 to the right, uncovering the port of the passage 25. Fluid can thereby flow from the left-hand end of the control cylinder 19 and be discharged from the discharge passage 23 to the

4

atmosphere. The port of the passage 26 is simultaneously opened to the inner space between the two piston lands, which is supplied with fluid under pressure from the pipe or duct 20. Thus pressure fluid is free to flow along the duct 26 to the lower side of the piston 28, in the work cylinder 27, and the piston 28 will thereby be moved to further open the valve 32, to admit an increased air supply to the combustion space. This increase in the air quantity causes a reduction in the exhaust gas temperature in the pipe 9 and the exhaust manifold. The temperature responsive mechanism, including the bulb 14, will therefore be actuated to move the piston to the left, to close the ports of the passages 25 and 26. As soon as this has taken place, the piston 28 is locked in the position in which it is set. The piston 28, being locked or fixed, will hold a valve 32 in a position which will produce the predetermined exhaust temperature in the exhaust manifold.

Any increase or decrease in the exhaust temperature will similarly cause the work piston to hunt for its proper position and when the work piston reaches its proper position, it is then locked in the proper setting by a return movement of the control piston into position to close the passages between the two cylinders.

By introducing any suitable compensating device between the heat responsive structure and the work piston, operated for example by the engine governor, any other desired load temperature relation can be automatically produced.

I claim:

- 35 1. The combination of an internal combustion engine having a combustion chamber, a combustion air passage extending thereto, and an exhaust passage extending therefrom; air compressing means for supplying charging air to said combustion air passage; a valve member between the air compressing means and the engine cylinder valves formed and adapted to vary the effective air admitting diameter of said combustion air passage; a heat responsive member positioned to respond to the heat of said exhaust passage; and an actuating connection between said heat responsive member and said valve member adapted to adjust the position of said valve member in response to heat conditions in said exhaust passage, and to lock it in adjusted position.
- 40 2. The combination defined in claim 1, in which the actuating connection includes an expansible fluid containing member.
- 45 3. The combination defined in claim 1, in which the actuating connection includes a cylinder, a piston therein, connected to said valve, a source of fluid pressure, and connections between said source of fluid pressure and said cylinder, at each side of said piston.
- 50 4. The combination defined in claim 1, in which the actuating connection includes a cylinder, a piston therein, connected to said valve, a source of fluid pressure, connections between said source of fluid pressure and said cylinder, at each side of said piston, and a control assembly, responsive to said heat responsive member, formed and adapted to close said connections when the valve member is in a position appropriate to the temperature conditions in the exhaust passage.
- 55 5. The combination defined in claim 1, in which the actuating connection includes a power cylinder, a piston therein, connected to said valve, a source of fluid pressure, connections between said source of fluid pressure and said power cyl-

inder, at each side of said piston, and a control assembly, including a control cylinder connected to said source of fluid pressure, a piston in said control cylinder, an actuating connection between said piston and the heat responsive member, and fluid passages between said cylinders.

6. In a control assembly for internal combustion engines having an air inlet passage and an exhaust passage, a heat responsive member responsive to the heat of gases in the exhaust passage, a valve formed and adapted to control the rate of flow of air through the air inlet passage, and an actuating connection between the heat responsive member and the valve, adapted to set the valve at the proper position to supply the air necessary to maintain a predetermined exhaust temperature, said actuating connection including a portion formed and adapted to lock the valve in adjusted position when the heat responsive member is satisfied.

7. The combination defined in claim 6, in which the actuating connection includes a master cylinder and a work cylinder, a piston in the work cylinder connected to the valve, fluid passages between the master cylinder and the opposite ends of the work cylinder, a pressure passage to an intermediate part of the work cylinder from a suitable pressure source, exhaust passages from opposite ends of the work cylinder and a piston in the work cylinder connected to the heat responsive member.

8. In an internal combustion engine, an intake passage, an exhaust passage, a charging valve independent of the engine for controlling the effective area of the intake passage and so the amount of charging air admitted, a hydraulic motor adapted to positively control the charging

valve, a motor control valve, a hydraulic circuit including the motor, control valve and the charging valve motor, a heat sensitive element in the exhaust passage and an actuating connection between the heat sensitive element and the control valve whereby the charging valve is actuated responsive to variations in exhaust temperature.

9. In an internal combustion engine, an intake passage, an exhaust passage, a charging valve independent of the engine for controlling the effective area of the intake passage and so the amount of charging air admitted, a hydraulic motor adapted to positively control the charging valve, a motor control valve, a hydraulic circuit including the motor, control valve and the charging valve motor, a heat sensitive element in the exhaust passage and an actuating connection between the heat sensitive element and the control valve whereby the charging valve is actuated responsive to variations in exhaust temperature, means for maintaining the hydraulic system constantly filled with hydraulic fluid whereby the charging valve is locked in the position in which it is placed responsive to the heat sensitive element.
